REEL

Jeremiah W. O'Brien, Pittsburgh, Pa., assignor
to United Engineering & Foundry Company,
Pittsburgh, Pa., a corporation of Pennsylvania

Application April 23, 1937, Serial No. 138,557

13 Claims. (Cl. 242—72)

This invention relates to collapsible reels for coiling metal strip and the like.

Heretofore various types of collapsible drums or reels for winding metal strip and the like have been provided. However, these have been open to the objection that they are relatively complicated necessitating considerable initial and maintenance cost. In addition, some reels have been made of such a multiplicity of parts, particularly in the strip-gripping mechanism, that they are not readily operated by the workman and, moreover, are apt to easily get out of proper operating order. Further, the problem of holding radially movable reel segments against collapsing movement when in the expanded position without distortion of the reel parts has long presented difficulties.

It is the general object of my invention to avoid and overcome the foregoing and other difficulties of known reel structures by the provision of sturdy, long wearing, easily operated, and relatively inexpensive mechanism adapted for coiling metal strip and the like.

Another object of my invention is to provide a collapsible reel which can readily be made of a type adapted to coil strip under heavy tension or of a lighter type adapted to rewind or handle strip under light loads.

Another object of my invention is to provide a collapsible reel having simplified and improved strip-gripping mechanism and flat-surfaced cams for operating the reel segments.

Another object of my invention is the provision of a collapsible reel having a construction particularly adapted to absorb and overcome distortion producing strains encountered by the reel in use.

Another object of my invention is to provide a collapsible reel in which radially movable reel segments carrying cam plates are controlled by an axially positioned shaft having rollers engaging the cam plates.

A more particular object of my invention is to provide, a collapsible reel for winding metal strip with the reel including a straight, cold-rolled, central shaft instead of the expensive, forged shaft employed on known types of reels.

Simplified strip-gripping mechanism is incorporated with the reel, and the reel parts and particularly the shaft are constructed so as to absorb and overcome distortion producing strains.

The shaft may comprise in part a relatively inexpensive cold-rolled shaft and the reel as a whole can readily be made of a heavy or a light construction.

In the accompanying drawings Fig. 1 is an end elevation of one embodiment of my invention; Fig. 2 is a longitudinal diametric section taken on line II—II of Fig. 1; Fig. 3 is a transverse cross-sectional view taken on line III—III of Fig. 2 and illustrating in full lines the reel in its expanded position and in dotted lines the reel in its collapsed position; Fig. 4 is a view similar to Fig. 3 but is of a modified form of my invention; and Fig. 5 is a view similar to Figs. 3 and 4 but is 10 of another modification of my invention.

While broadly adapted to coil and handle material of various kinds, my improved reel is particularly adapted to coil relatively wide, thin, metal strip and hence has been so illustrated and 15 will be so described.

Specifically considering the embodiment of the invention illustrated in Figs. 1 to 3 of the drawings and constituting a relatively light-weight, rewinding type of reel, the numeral 10 indicates 20 generally a cold-rolled shaft of substantially uniform diameter along its length which is driven in any suitable manner and supported in cantilever bearings. A shaft of this character is very easily manufactured in accordance with known 25 practice and is considerably less expensive than a forged or other cam shaft of special size, such as often employed in reels of the general character described. Journalized for limited rotary movement on the shaft head is a radially fixed reel 30 segment 12 having relatively light walls and including suitable means for receiving and clamping an end of a strip of metal to be coiled. In this embodiment of my invention these means take the simplest possible form, i. e., an inclined slot 13. Preferably the segment 12 is formed 35 with an integral hub 14 at one end and a removable hub 16 is secured as at 18 to the fixed segment to achieve the mounting of the segment on the shaft 10. The hubs 14 and 16 are formed 40 with aligned bushings 20 and 22 which journal the shaft 10. The limited relative rotary movement of the radially fixed segment 12 on the shaft 10 is preferably determined by the provision 45 of spaced stops 26 and 28 which may be formed integrally with the hub 14 of the segment 12. Keyed or otherwise secured to the shaft 10 is a 50 collar 30 formed with a finger 32 which extends between the stops 26 and 28. The collapsing and expanding action of the drum is controlled by the limited relative rotary movement of the shaft 10 and the fixed reel segment 12, as hereafter more 55 fully described.

Completing the contour of the reel are radially 55

movable reel segments 36 and 38 having relatively light-weight walls which segments are pivotally secured by longitudinally extending pins 40 and 42 to the radially fixed segment 12. Provided upon the inner sides of the movable segments 36 and 38 are cam surfaces which are preferably in the form of cam plates 46 and 48 having flat faces which are easily machined and which are positioned as shown to effect the desired cam action. The segments 36 and 38 are resiliently held towards each other and are moved to collapsed position by springs 47 carried by pins 49 fastened to the segments.

The shaft 10 carries a hub 50 which is secured thereto as by a key 52 and mounted upon the hub are two sets of aligned rollers 54 and 56 which construction expedites and simplifies the construction and assembly of the reel. Preferably, as shown in Figs. 2 and 3, the hub 50 is formed with radially extending lugs 58 which carry axles 60 and 62 positioned parallel to each other and to the shaft 10. The rollers 54 and 56 are provided with bushings 66 and 68 rotatably carried upon the axles 60 and 62, respectively, between the lugs 58. Thus, as best evidenced in Fig. 2, a plurality of longitudinally spaced areas of contact between the cam plates 46 and 48 and the rollers 54 and 56, and thus the hub 50 and shaft 10, are provided. The hub 50, due to its shape and the beam-like structure provided by the extra metal 51, serves to strengthen the shaft 10, particularly in the direction of the radial thrust of the movable reel segments 36 and 38, and largely absorbs and overcomes strains tending to distort the reel.

Preferably the surfaces of the cam plates 46 and 48 are at a slight angle to true radii of the shaft 10 so that lines 70 drawn perpendicular to the surfaces from the points of contact of the rollers 54 and 56 therewith pass to the same side of the axis of the shaft. By this arrangement forces applied to the circumference of the reel and tending to collapse it are employed to almost overcome the frictional resistance against collapse by causing torque tending to rotate the shaft 10 relative to the fixed reel segment 12.

Formed integrally with the fixed reel segment 12 or as shown secured thereto is a braking surface or drum 72 which can be braked in any suitable manner to effect the expanding or collapsing movement of the reel.

The operation of the reel should be evident from the foregoing description when considered in conjunction with the drawings. Briefly summarizing, however, an end of the metal strip is inserted in the slot 13 of the radially fixed reel segment 12 and the reel is revolved in the direction shown by the arrow in Fig. 3. Since the driving of the reel is effected by rotation of the shaft 10, it will be evident that the finger 32 of collar 30 moves into engagement with the stop 28 as shown in Fig. 1, which moves the rollers 54 and 56 into the full line relation indicated in Fig. 3 with the cam plates 46 and 48. In other words, the reel is in its fully expanded position. Continued rotation of the reel as effected by positive rotation of the shaft 10 coils any desired amount of strip metal upon the reel. When the end of the metal strip to be coiled has been reached or when it is desired to stop the coiling action, the shaft 10 is, of course, stopped, usually by braking the shaft 10, as, for example, dynamic braking of an electric motor drive. The relatively high momentum of the reel and the metal 75 coil assisted by the off-center turning forces de-

scribed above turns the reel relative to the shaft 10 so that finger 32 moves over into engagement with stop 28 (see Fig. 1). This relative rotary movement of the shaft 10 and the radially fixed reel segment 12 causes the rollers 54 and 56 carried by the hub 50 to move to the dotted line position shown in Fig. 3. Due to the cam action of the cam plates 46 and 48, the radially movable reel segments 36 and 38 likewise move to the dotted line position of Fig. 3, thereby effecting 10 the collapsing of the reel and permitting the withdrawal of the coiled metal from the end of the collapsed reel.

In certain instances, it may be undesirable to dynamically brake the shaft 10 and in cases of 15 this character the brake surface or drum 72 may come into play. This surface can be positively braked and the motor or other means of rotating the shaft 10 driven in reverse to turn the finger 32 of collar 30 from contact with the stop 20 28 into engagement with the stop 26 to thereby collapse the reel.

Once the coil of material has been removed or even before it has been removed and it is desired to resume the winding or coiling operation, the 25 continued rotation of the shaft 10 in the direction indicated by the arrow in Fig. 3 will cause the relative rotary movement of the shaft 10 and the radially fixed reel segment 12 to move the parts of the reel from the dotted to the full line 30 or expanded position of Fig. 3.

In the form of the invention shown in Fig. 4 the parts which are similar or identical to those heretofore described are referred to only generally, it being understood that except where specifically described as different the several embodiments of my invention are alike. Specifically, the numeral 76 indicates a cold-rolled shaft upon which is mounted a radially fixed reel segment 78 for limited relative rotary movement there- 40 with. Hinged to the radially fixed reel segment 78, as by pins 80 and 82, are radially movable reel segments 84 and 86 which are preferably formed at their meeting ends with interlocking tongue and groove portions indicated generally at 45 88.

The radially movable reel sections 84 and 86 are provided respectively with cam plates 90 and 92 having flat surfaces in engagement with rollers 94 and 96 carried by longitudinally extending shafts 98 and 100 mounted upon a hub portion 102 keyed to the shaft 76. The hub portion 102 is formed with a longitudinally extending strengthening rib 104 so that forces tending to circumferentially compress the reel and move the radially movable sections 84 and 86 inwardly are absorbed and overcome by the relatively strong and radially deep construction of the shaft 76 and strengthening hub 102.

Preferably the surfaces of the cam plates 90 and 92 are not at a right angle to radii of the shaft 76 but instead are formed perpendicular to lines 106 which pass to the same side of the axis of the shaft 76. By this construction any desired part of the frictional forces resisting the collapse of the reel may be overcome since the radial thrust of the movable sections 84 and 86 creates a torque tending to turn the shaft 76 relative to the radially fixed reel segment 78.

This embodiment of my invention includes an 70 improved simplified form of strip-gripping or clamping mechanism which comprises an arm 108 ordinarily formed integral with the hub 102 and extending as illustrated in Fig. 4 to a point adjacent a slot 110 formed across the width of 75

the radially fixed reel segment 78, through which slot the strip to be clamped by the arm can be inserted. The arm 108 is provided with a clamping bar 112 which cooperates with a clamping bar 114 fastened to the radially fixed reel segment 78. Preferably the cooperating bars 112 and 114 are formed with complementary tongue and groove cross-sectional contours so that the end of the strip received therebetween is firmly clamped upon movement of the arm 108 from the dotted to the full-line position. It should be understood that the engagement of the arm 108 with the radially fixed reel segment limits the reel expanding rotary movement of the shaft 76. In order to limit the relative rotary movement between the shaft 76 and the radially fixed reel segment 78 in the other or collapsing direction, I preferably provide lugs 116 on the hub 102 which engage with a shoulder 118 formed on the reel segment 78.

The operation of this embodiment of my invention is basically the same as that above described and illustrated in Figs. 1 to 3. However, the operation will now be briefly reviewed having particular reference to the strip-clamping mechanism. With the reel parts in the collapsed position as shown in dotted lines of Fig. 4, the end of a metal strip is inserted in the slot 110 so that it is positioned between the clamp bar 114 and the clamp bar 112. Driving the shaft 76 in the direction shown by the arrow causes relative rotary movement of the shaft and the radially fixed reel segment 78 to move the arm 108 to its full-line position and thereby force the clamping bar 112 tightly into engagement with the strip to hold it against the clamp bar 114. The same relative rotary movement by the shaft 76 and the radially fixed reel segment 78 effects the movement of the reel segments 84 and 86 to their expanded position shown in full lines. The coil of strip will now be wound on the reel as desired and when it becomes necessary to collapse the reel relative rotary movement between the shaft 76 and the reel segment 78 effects collapse of the reel, as will be understood, at which time the arm 108 and clamp bar 112 return to the dotted line position to release the end of the strip. In the relative rotary movement last mentioned the lugs 116 engaging with the shoulder 118 limit such movement.

The embodiment of my invention shown in Fig. 5 is generally similar to the several embodiments discussed heretofore and illustrated in Figs. 1 to 4 and the similar parts will, therefore, only be generally described here. The form of my invention shown in Fig. 5 is particularly adapted for coiling metal strip under relatively heavy tension and is of the so-called heavy-duty type. The numeral 120 indicates a central shaft 60 which may comprise a cold-rolled center and a surrounding hub portion as contained in the two embodiments of my invention heretofore described. Preferably, however, the shaft 120 is cast or forged and then machined to the contour illustrated. The shaft 120 journals for limited relative rotary movement a radially fixed reel segment 122, ordinarily by means such as heretofore described, and completing the contour of the reel are radially movable reel segments 70 124 and 126 formed with interfitting ends 128 and hinged to the radially fixed reel segment 122 as by pins 130 and 132. The radially movable reel segments 124 and 126 respectively carry flat-surfaced cam plates 134 and 136 which 75 operate with rollers 138 and 140 journaled by

suitable bearings upon axles 142 and 144 extending longitudinally of the shaft 120 as illustrated in the drawings. Similar to the embodiments of my invention above described, the surfaces of the cam plates 134 and 136 are perpendicular to lines 146 which pass to one side of the pivotal axis of the shaft 120 so as to provide a friction overcoming torque as heretofore recited.

The mechanism for gripping or clamping the end of a strip to the reel in this embodiment of my invention includes an opening 150 formed in the radially fixed reel segment 122 and receiving a plurality of rocker or clamp arms 152 pivotally mounted upon a pin 154 carried by the reel segment 122. The rocker arms 152 are secured to a clamping bar 156 which cooperates with a clamping bar 158 secured to the fixed reel segment 122. The clamp bar 156, as will be seen in Fig. 5, forms a part of the reel surface when the reel is expanded. The forces imparted to the bar by the strip and tending to move the bar radially inwardly are carried directly to the shaft 120.

The shaft 120 is formed with lugs 160 which 25 engage with a cam plate 162 carried by the rocker arms 152 and operating to swing the rocker arms 152 about the pin 154 in order to clamp metal strip between the clamping bars 156 and 158. The lugs 160 also engage with a shoulder 30 164 formed on the reel segment 122 to limit relative rotary movement of the shaft 120 and the reel segment 122 in the reel expanding direction. To limit this same relative movement in the other or reel collapsing direction lugs 166 35 likewise formed on the shaft 120 engage with a shoulder 168 formed on the reel segment 122. The rocker arms 152 are provided with finger portions 170 which engage with the lugs 160 upon movement of the reel parts to collapsed 40 position.

It will be recognized that the basic operation of this embodiment of my invention is substantially the same as that heretofore described in detail in conjunction with the several other embodiments heretofore considered except for the operation of the strip-gripping mechanism. This mechanism as should be understood is in the dotted position when the reel is collapsed. The strip end can readily be inserted between the 45 clamping bars 156 and 158. Upon driving the shaft 120 in the direction of the arrow to coil strip thereon the lugs 160 engaging with the cam plate 162 move the clamping bars 156 and 158 into clamping relation with the strip. After 50 the desired amount of strip has been coiled the reel is collapsed as above described by turning the shaft 120 relative to the reel segment 122 in a direction opposite to the arrow, which operation causes the lug 160 to engage the fingers 170 and tilt the rocker arms 152 to move the clamping bars 156 and 158 apart and to simultaneously collapse the reel in movement limited by the engagement of lug 166 with the shoulder 55 168.

From the foregoing it will be recognized that the objects of my invention have been achieved by the provision of a relatively simple inexpensive reel readily adapted to manufacture in either the heavy-duty tension-type or a light-walled rewinding type. The strip-gripping mechanism is simplified and improved and the strength of the central shaft of the reel to resist strains and forces tending to distort the reel has been improved so that these distortion- 65 70 75

producing factors are absorbed and overcome. A reel constructed in accordance with my invention is readily collapsed or expanded even though strip under considerable tension is coiled 5 thereon in that the compressive forces of the strip are directed to overcome frictional resistance against collapse.

While several embodiments of my invention have been illustrated and described in detail, it 10 should be understood that my invention is not limited thereto or thereby but is defined in the appended claims.

I claim:

1. A collapsible reel for coiling metal strip and 15 the like, comprising a shaft, a radially fixed reel segment journaled on the shaft, means on said segment to secure the end of a metal strip thereto, means limiting the relative movement of the shaft and the segment, radially movable reel 20 segments completing the contour of the reel and pivotally secured to the radially fixed segment, flat-surfaced cam plates fixed to the inner sides of the radially movable segments near the movable ends thereof and having surfaces perpendicular to lines passing to one side of the axis 25 of the shaft, a pair of axles mounted on the shaft in parallel relation to each other and to the shaft and each positioned in juxtaposition to a cam plate, a plurality of rollers journaled 30 on each axle and engaging with the juxtaposed cam plate, said shaft having a relatively heavy strengthening rib of metal between the rollers, and a braking surface on the fixed reel segment to facilitate relative rotary movement of the 35 shaft and reel segments to collapse the reel.

2. A collapsible reel for coiling metal strip and the like, comprising a shaft, a radially fixed reel segment journaled on the shaft, means on said segment to secure the end of a metal strip there- 40 to, means limiting the relative movement of the shaft and the segment, radially movable reel segments completing the contour of the reel and pivotally secured to the radially fixed segment, cam means having substantially flat surfaces, said 45 cam means being positioned on the inner sides of the radially movable segments near the movable ends thereof, a pair of axles mounted on the shaft in parallel relation to each other and to the shaft and each positioned in juxtaposition 50 to a cam means, a plurality of rollers journaled on each axle and engaging with the juxtaposed cam means, said shaft having a relatively heavy strengthening rib of metal between the rollers, and a braking surface on the fixed reel segment 55 to facilitate relative rotary movement of the shaft and reel segments to collapse the reel.

3. A collapsible reel for coiling metal strip and the like, comprising a cold rolled shaft, a radially fixed reel segment journaled on the shaft, 60 means on said segment to secure the end of a metal strip thereto, means limiting the relative movement of the shaft and the segment, radially movable reel segments completing the contour of the reel and pivotally secured to the radially fixed segment, cam plates fixed to the inner sides of the radially movable segments near the movable ends thereof and having surfaces perpendicular to lines passing to one side of the axis of the shaft, a hub secured to the 65 shaft and positioned inside the reel in radial alignment with the segments thereof, a pair of axles mounted on the hub in parallel relation to each other and to the shaft and each positioned in juxtaposition to a cam plate, a plurality of rollers journaled on each axle and engaging with the juxtaposed cam plate, and a braking surface on the fixed reel segment to facilitate relative rotary movement of the shaft and reel segments to collapse the reel.

4. A collapsible reel for coiling metal strip and the like, comprising a cold rolled shaft, a radially fixed reel segment journaled on the shaft, means on said segment to secure the end of a metal strip thereto, means limiting the relative movement of the shaft and the segment, radially movable reel segments completing the contour of the reel and pivotally secured to the radially fixed segment, cam means on the inner sides of the radially movable segments near the movable ends thereof, a hub secured to the shaft and positioned inside the reel in radial alignment with the segments thereof, a pair of axles mounted on the hub in parallel relation to each other and to the shaft and each positioned in juxtaposition to a cam means, a plurality of rollers journaled on each axle and engaging with the juxtaposed cam means, and a braking surface on the fixed reel segment to facilitate relative rotary movement of the shaft and reel segments to collapse the reel.

4. A collapsible reel for coiling metal strip and the like, comprising a cold rolled shaft, a radially fixed reel segment journaled on the shaft, means on said segment to secure the end of a metal strip thereto, means limiting the relative movement of the shaft and the segment, radially movable reel segments completing the contour of the reel and pivotally secured to the radially fixed segment, cam means on the inner sides of the radially movable segments near the movable ends thereof, a hub secured to the shaft and positioned inside the reel in radial alignment with the segments thereof, a pair of axles mounted on the hub in parallel relation to each other and to the shaft and each positioned in juxtaposition to a cam means, a plurality of rollers journaled on each axle and engaging with the juxtaposed cam means, and a braking surface on the fixed reel segment to facilitate relative rotary movement of the shaft and reel segments to collapse the reel.

5. A collapsible reel for coiling metal strip and the like, comprising a cold rolled shaft, a radially fixed reel segment journaled on the shaft, means on said segment to secure the end of a metal strip thereto, means limiting the relative movement of the shaft and the segment, radially movable reel segments completing the contour of the reel and pivotally secured to the radially fixed segment, cam means on the inner sides of the radially movable segments near the movable ends thereof, a hub secured to the shaft and positioned inside the reel in radial alignment with the segments thereof, a pair of axles mounted on the hub in parallel relation to each other and to the shaft and each positioned in juxtaposition to a cam means, a plurality of rollers journaled on each axle and engaging with the juxtaposed cam means, and means to facilitate relative rotary movement of the shaft and reel segments to collapse the reel.

6. A collapsible reel for coiling metal strip and the like, comprising a cold rolled shaft, a radially fixed reel segment journaled on the shaft, said segment having a fixed slot to receive the end of a metal strip, means limiting the relative movement of the shaft and the segment, radially movable reel segments completing the contour of the reel and pivotally secured to the radially fixed segment, cam plates fixed to the inner sides of the radially movable segments near the movable ends thereof, a hub secured to the shaft and positioned inside the reel in radial alignment with the segments thereof, a pair of axles mounted on the hub in parallel relation to each other and to the shaft and each positioned in juxtaposition to a cam plate, a plurality of rollers journaled on each axle and engaging with the juxtaposed cam plate, and a braking surface on the fixed reel segment to facilitate relative rotary movement of the shaft and reel segments to collapse the reel.

7. A collapsible reel for coiling metal strip and the like, comprising a cold-rolled shaft, a radially fixed reel segment journaled on the shaft, said segment having a slot of fixed dimensions to receive the end of a metal strip, means limiting the relative movement of the shaft and the segment, radially movable reel segments completing the contour of the reel and pivotally secured to the radially fixed segment, cam means on the inner sides of the radially movable segments near the movable ends thereof, a hub secured to the shaft and positioned inside the reel in radial alignment with the segments thereof, a pair of axles mounted on the hub in parallel relation to each other and to the shaft and each positioned in juxtaposition to a cam means, a plurality of rollers journaled on each axle and engaging with the juxtaposed cam means, and a braking surface on the fixed reel segment to facilitate relative rotary movement of the shaft and reel segments to collapse the reel.

- inner sides of the radially movable segments near the movable ends thereof, a hub secured to the shaft and positioned inside the reel in radial alignment with the segments thereof, a pair of 5 axles mounted on the hub in parallel relation to each other and to the shaft and each positioned in juxtaposition to a cam means, and a plurality of rollers journaled on each axle and engaging with the juxtaposed cam means.
- 10 8. A collapsible reel, comprising a shaft, a radially fixed reel segment mounted on the shaft, and having a slot to receive the end of a metal strip, means providing limited relative movement of the shaft and the segment, radially movable 15 reel segments completing the contour of the reel, flat-surfaced cams on the inner sides of the radially movable segments, a hub secured to the shaft and positioned inside the reel in radial alignment with the segments thereof, and rollers 20 journaled on the hub and engaging with the cams.
9. A reel, comprising a central shaft, a hub mounted for relative rotary movement at each end of the shaft, a radially fixed segment supported by the hubs, a collapsible segment pivotally secured to the fixed segment, cam means on the collapsible segment, and means secured to the shaft and engaging with the cam means so that relative rotary movement of the shaft and 25 fixed segment effects the collapse or expansion of the reel, said means on the shaft including a beam-like structure which strengthens the shaft in the direction of the radial thrust of the collapsible segment.
- 30 10. A reel, comprising, a central shaft, a hub mounted for relative rotary movement at each end of the shaft, a radially fixed segment supported by the hubs and having a slot therein adapted to receive the end of a strip of material, 35 a pair of collapsible segments pivotally secured to the fixed segment, cam means on the collapsible segments, rollers carried by the shaft and engaging with the cam means so that relative rotary movement of the shaft and fixed segment effects the collapse or expansion of the reel, and a clamping arm integrally associated 40 with the shaft and movable upon the expansion of the reel into clamping relation with material extending into the slot.
11. A collapsible reel comprising a shaft, a radially fixed reel segment rotatably mounted on the shaft, radially movable reel segments hinged 5 to the radially fixed reel segment and completing the contour of the reel, means associated with the shaft and radially movable reel segments for collapsing and expanding the reel upon relative rotary movement of the shaft and radially 10 fixed reel segment, means integrally associated with the shaft and adapted to clamp against the radially fixed reel segment to secure the end of strip material to the reel, said last-named means limiting reel expanding movement between the shaft and the radially fixed reel segment, and other means on the shaft engageable with the fixed reel segment to limit the reel 15 collapsing movement between the segment and the shaft.
12. A collapsible reel comprising a shaft, a radially fixed reel segment rotatably mounted on the shaft, radially movable reel segments hinged to the radially fixed reel segment and completing the contour of the reel, means associated with the shaft and radially movable reel 20 segments for collapsing and expanding the reel upon relative rotary movement of the shaft and radially fixed reel segment, and means integrally associated with the shaft and adapted to clamp 25 against the radially fixed reel segment to secure the end of strip material to the reel, said last-named means limiting reel expanding movement between the shaft and the radially fixed reel segment.
13. A collapsible reel comprising a shaft, a radially fixed reel segment rotatably mounted on the shaft, radially movable reel segments hinged to the radially fixed reel segment, means associated with the shaft and radially movable reel 30 segments for collapsing and expanding the reel upon relative rotary movement of the shaft and radially fixed reel segment, and means integrally associated with the shaft and adapted to clamp 35 against the radially fixed reel segment to secure the end of strip material to the reel.

JEREMIAH W. O'BRIEN,
